[57] CLAIM

The ornamental design for a circular mount for ribbed floor mats, as shown and described.

DESCRIPTION

FIG. 1 is a top front perspective view of a circular mount for ribbed floor mats showing our new design;

FIG. 2 is a top plan view thereof;

FIG. 3 is a front elevation view thereof, the rear elevation view being a mirror image thereof;

FIG. 4 is a side elevation view thereof; the opposite side elevation view being a mirror image thereof; and

FIG. 5 is a bottom front perspective view thereof.

FIG. 1

FIG. 2

FIG. 3

FIG. 4

FIG. 5
